UNITED STATES PATENT OFFICE.

FRANK J. GILROY, OF BUFFALO, NEW YORK.

CAR-DOOR.

1,255,154.

Specification of Letters Patent.

Patented Feb. 5, 1918.

Application filed April 3, 1915. Serial No. 19,030.

To all whom it may concern:

Be it known that I, FRANK J. GILROY, a citizen of the United States, residing at Buffalo, in the county of Erie and State of

5 New York, have invented certain new and useful Improvements in Car-Doors, of which the following is a specification, reference being had therein to the accompanying drawing.

10 The object of this invention is to provide metallic devices to replace the internal boarding commonly employed in cars to be loaded with grain, and with this object in view I provide a vertically divided two-part closure of which one part may slide horizontally past the other, to open the side of the doorway, while both parts may swing together, from closing position, on a horizontal axis above the lower edge of the closure.

20 In the accompanying drawings.

Figure 1 is a side elevation of a portion of a car provided with my devices.

Fig. 2 is an enlarged section on the line 25 2—2, Fig. 1, parts being broken away, and the doorway being fully closed.

Fig. 3 is a vertical section at the doorway showing the closing plates when materially overlapped by the opening of one of them.

30 Fig. 4 is an axial section of the middle portion of one of the plate-supporting bars which engage the door posts.

Fig. 5 is a section at 5—5, Fig. 4 looking toward the left.

35 Fig. 6 is a view looking from the right in Figs. 1, 2, parts being broken away to show the end of the post-engaging rod and its end bearing.

In these views, A represents the side of 40 a freight car, and B, B' two overlapping metal plates sliding horizontally one upon the other to open and close the lower part of the doorway, the plates extending above the line for loads of loose granular material.

45 Each plate has its four margins stiffened by one or more commercial angle irons fixed to the plate and to each other where two are used. As shown, each plate has fixed to that margin next the door post C an angle iron D, and to its opposite margin two angle irons E, F riveted together to form oppositely turned hooks which engage as in Fig. 2 when the doorway is fully closed. The plate B has at top and bottom similar angle irons E', F', which form hooks to engage the upper and lower margins of the

plate B' which are stiffened by angle irons G. For clearness, all these angle irons are shown somewhat exaggerated in size and separation.

60 The plates are detachably held in position by telescoping horizontal rods shown as three in number and located near the top, bottom, and middle of the structure. Each rod involves a two part tube H having 65 its parts connected by a turnbuckle I and slideable in bearings J, K carried by the plate B, and further of a second smaller tube or rod telescoping in the tube H and sliding in a bearing M fixed to the distant margin of 70 the plate B'. At the bearing J, a plug N is fixed in the end of the tube H and provided with a non-circular flange N' sliding without rotation in a way P in the bearing and having a tapered end to enter an aperture in the door post, which is preferably 75 provided with a bushing O. To the opposite end of the tube H is fixed a non-circular sleeve K' which slides in a corresponding way in the bearing K and diminished in size 80 near one end to receive and guide the tube L which is at will locked therein, when the rod is fully extended, by suitable means, for example, a cotter pin. The bearing M at the opposite end of the tube L and coating 85 parts are similar in every way to the corresponding parts at the bearing J.

In use, the rods being within the lateral margins of the plates, the plates are placed in the doorway as in Fig. 1, and by operating the turnbuckles the ends of each are projected into engagement with the door posts, as indicated in Figs. 1 and 2. Strips R are then fixed to the car floor to close crevices at the lower edges of the plates, and the car 95 is ready for loading.

When it is to be unloaded, the turnbuckles serve to withdraw each end of the rods, since no part of the latter can rotate. Usually, the lower and middle rods only are thus retracted, the cleats R are removed, and the closure swings on the upper rod allowing discharge across the whole width of the doorway. When the closure is not to be used the two plates are moved on each other narrowing the structure to practically half its extended width, in which form it is far more easily handled, one man being able to move it to any position, within or without the car, without difficulty.

110 What I claim is:

1. The combination with a grain carrying

car having suitable holes in its door posts, of a closure for the lower part of the door opening, consisting of two laterally overlapping sliding door sections adapted to interlock marginally when extended to fit between the posts, telescoping rods mounted on the exterior of the sections and extending across the doorway to enter said holes when extending beyond the door margins, and 10 means for forcibly projecting the rods into said holes.

2. The combination with a car door consisting of two horizontally sliding sections overlapped at their vertical sides and adapted 15 to interlock when extended to fill the space between the car door posts, of a series of horizontal rods, each consisting of two telescoping sections, mounted upon the outer faces of the door sections to slide one within 20 the other when one of said sections slides with respect to its companion, means for forcibly sliding the rod sections in either direction to control their engagement with the door posts, and means for positively locking 25 the rods in post engaging position.

3. The combination with a car door consisting of two horizontally sliding laterally overlapping sections adapted for marginal interlocking when fully extended, of a series 30 of horizontal rods each consisting of two telescoping sections extending from side to side of the door, one of the sections being mounted to slide in bearings near the margins of one of the door sections and the second telescoping with the one and sliding in 35 a bearing at the other margin of its door section, means for forcibly extending each rod, and means for locking together the sections of each when extended.

40 4. The combination with a car provided with suitable rod-receiving holes in its door posts, of a door consisting of two overlapped horizontally sliding door sections adapted to interlock marginally when extended and to

swing in a vertical plane while fitting between the door posts, horizontal rods mounted upon the sections and extending across the door near the top and bottom of the same respectively and each consisting of two telescoping sections mounted to slide in 45 bearings upon the door sections, means for projecting the rod sections oppositely into the corresponding holes in the door posts, and means for locking the extended rod sections against retraction; the engagement of 50 the upper rod with the door posts being pivotal.

5. The combination with a grain carrying car having suitable rod-receiving holes in its door posts, of a closure consisting of two laterally overlapping sliding door sections normally fitting between the door posts, telescoping rods mounted on the sections and extending from side to side of the door, means for sliding the rod sections oppositely 60 into and out of engagement in the corresponding holes in the door posts, and external strips secured to the car floor along 65 the outer faces of the door sections.

6. The combination with two horizontally 70 sliding door sections each of thin metal having its margins stiffened by angle iron and adapted to interlock its companion when the two extend from side to side of a doorway, of a series of hollow, horizontal, extensible 75 rods each slidably held in bearings upon one of the door sections, a corresponding series of rods sliding in bearings upon the other door section and always telescoping the hollow rods, respectively, and means for rigidly 80 connecting the telescoping rods.

In testimony whereof I affix my signature in presence of two witnesses.

FRANK J. GILROY.
